UNITED STATES PATENT OFFICE.

HENRY HORAN, OF EAST ORANGE, NEW JERSEY, ASSIGNOR TO THE HARTFORD CARPET COMPANY, OF HARTFORD, CONNECTICUT.

DESIGN FOR A CARPET.

SPECIFICATION forming part of Design No. 12,823, dated March 21, 1882.

Application filed February 11, 1882. Term of patent 3½ years.

To all whom it may concern:

Be it known that I, HENRY HORAN, of East Orange, in the county of Essex and State of New Jersey, have invented a new and original 5 Design for Carpets, of which the following is a specification.

This invention relates to a new and original 10 design for carpets and similar fabrics; and it consists in the novel grouping and configuration of figures hereinafter more fully described.

The accompanying photograph illustrates a 15 face view of a carpet having my new design.

A is a ground field ornamented by various 20 small geometric figures in irregularly-shaped 15 groups, as shown. On this field, and traversing portions of it, are the flower-and-leaf groups B, C, D, E, and F.

B is the largest group, and has as its center 25 the figure a, which consists of a leaf mass with two fern-leaves below and one on each side. On the left is a projecting twig, as also on the right, and below and to the left is a bunch of narrow leaves. Projecting from a above and to the left is the flower-and-leaf group b. Di- 30 rectly above a, and springing from it, is the group c, consisting of a large central flower and a smaller flower on each side and a leaf cluster, and above ferns which spread upward and outward. Above and to the right of a, and 35 arranged on a forking branch projecting from a, is the leaf-and-flower group d. The upper fork terminates in e—a scattered group of circular flowers, leaves, and twigs—and the lower fork in a similar but more scattered group, f,

35 shown in part on each side of the photograph.

C is a group directly below the group B. It has at its center the leaf cluster g, which has a twig and a bud sprig below, and to the left a twig bearing a leaf. To the right of g, and 40 connected with it, is the circular flower group h, with two ferns below and a forking twig between them and a twig bearing a leaf above. Projecting from the left of g, and arching over it toward the right, is the scattered twig-and- 45 leaf group k.

D is a flower-and-leaf group, shown in part

on one side and in part on the other side of the photograph. It has as its center the leaf cluster l, which includes a fern projecting to the left. Below l is the figure m, projecting from l—a twig bearing circular flowers and buds. Above l, and projecting from it, is n—a branching twig with flowers.

E is a flower-and-leaf group, also shown in 55 part on each side of the photograph. It has as its center the leaf group o, having a small twig and flower projecting to the right, and to the left a small leaf spray below o, and projecting from it toward the right is the cluster p—a branch bearing small leaves and circular 60 flowers. Above o, and projecting from it, is the flower-and-leaf cluster q.

F, shown in part at each end of the photograph, is a small leaf cluster having projecting 65 twigs and sprays.

These various groups are scattered loosely 70 over the ground A, and the design as a whole presents an open appearance between and around the larger clusters, causing them to stand out prominently.

I claim—

1. The design for carpets, consisting of the 75 ground A, substantially as shown.

2. The design for carpets, consisting of the group B, (including a b c d e f,) substantially 75 as shown.

3. The design for carpets, consisting of the group C, (including g h k,) substantially as shown.

4. The design for carpets, consisting of the 80 groups B, (including a b c d e f,) C, (including g h k,) D, (including l m n,) E, (including o p q,) and F, substantially as shown.

5. The design for carpets, consisting, of the groups B, (including a b c d e f,) C, (including 85 g h k,) D, (including l m n,) E, (including o p q,) and F, and the ground A, substantially as shown.

HENRY HORAN.
